UNITED STATES PATENT OFFICE

ALFRED E. OSWALD, OF HACKENSACK, NEW JERSEY, ASSIGNOR TO UNDERWOOD ELLIOTT FISHER COMPANY, OF NEW YORK, N. Y., A CORPORATION OF DELAWARE

WORD COUNTING REGISTER FOR TYPEWRITERS

Application filed March 30, 1929. Serial No. 351,213.

The invention relates to electrically operated word-counting devices used in connection with typewriting machines.

The object is to count the words written, and display the total. The words are counted preferably in a manner to comply with the prevalent ruling in speed-contests, which requires that a certain number of strokes, regardless whether they be type or space bar strokes, shall be deemed to constitute the length of an average word.

There have been used standard work-sheet-blanks bearing marginal markings indicating the number of words up to each full line, such markings being based on the experience that, say, five standard letter-spaces will, on the average, be equivalent to one word written. In supplementing such expedients, the counter will register five strokes as one word.

The counter is electrically operated and includes an array of large dials actuated from the typewriter-key depressions through relay effect, said dials being large enough to display numbers visible from a distance and thus advertising the speed of the contestant. Relay means may include a "strokes-device" for converting the continuous sequence of typewriter-key strokes into periodical actuations of said dials, whereby the period or interval represents the number of strokes which is assumed to constitute the average word.

A novel contact-device upon the typewriter sends an electrical impulse to the counter indiscriminately at every type and space bar stroke. Every stroke reflects in the "strokes-device" of the counter, which is designed to respond to rapid typewriter-strokes. The office of the "strokes-device" is to divide a continuous sequence of strokes into intervals, each interval including a fixed number of strokes representing the length of a word to be registered in the counter. In other words, the "strokes-device" accumulates a fixed number of typewriter-strokes, and at the end of

each such period causes the dials to register a word. The "strokes-device" at the end of each cycle or period will trip a relay-switch to advance the dials. Other relayed currents may serve to carry over movement from one dial to the dial of the next higher order.

It is a feature of the construction that the dials in the preferred form of rings, while large enough for impressive display, may house substantially the whole actuating mechanism of the counter. By thus utilizing the space within said rings, the counter may form a convenient unit.

There is provided a friction drive for the dials, whereby friction-rollers motor-driven through the intermediary of brake-devices are constantly tending to rotate the dials, which latter are controlled in their stepwise movement by certain electromagnetically operated escapement-mechanism. Arrangement is made for electric relay means to carry over the movement from dial to dial.

Other features regarding the operation of said dials lie in a mechanism including a push-button or handle for automatically returning the dials to zero position.

Features are found in the construction of the "strokes-device" which constitute an escapement-device. An escapement-wheel tends to rotate under the continuous tension of a slightly energized motor herein called the "strokes-motor". In addition to a driving motor for said dials, the "strokes-motor" renders the counter fully automatic, eliminating completely any manipulation in the normal operation thereof. Through a shock-absorbing friction-device the "strokes-motor" is allowed to stepwise advance the escapement wheel, while an escapement-rocker or electromagnet responds to the primary impulse from each typewriter-stroke so as to control stepwise movement of said escapement-wheel. Arrangement may be such that each revolution of said escapement-wheel represents the period in which the associated

relay-switch is to be tripped to count a word in the dials.

A novel contact-device is mounted upon the typewriter to transmit every typewriter-stroke to the counter. The contact-device includes important features in itself which make for snappy and reliable operation, and has the inherent quality of not impairing to the slightest amount of touch of the typewriter.

Other features are found in the manner of assembling, combining and manufacturing the elements of the counter.

Other features and advantages will hereinafter appear.

In the accompanying drawings, Figure 1 shows a general perspective of an encased word-counter with parts broken away to display the interior arrangement of the counter.

Figure 2 is a section through an Underwood typewriter, showing the necessary elements for operating the key-controlled electrical contact-device provided upon the machine.

Figure 3 is a detail view taken from Figure 2, showing the contacts as normally open.

Figure 4 is a similar detail, showing the contacts closed, as upon a typewriter-key depression.

Figure 5 is a detail perspective, showing the driving motor and the "strokes-device" of the counter as an assembly unit.

Figure 6 is a detail taken from Figure 5, showing the main relay-switch has controlled by the "strokes-device".

Figure 7 is a view upon the left-hand side of the counter, particularly displaying the power-drive for the dials and showing detachable cable-connections as involved in the wiring system in the counter.

Figure 8 is a view upon the right-hand side of the counter, displaying more clearly escapement-mechanisms arranged within the dials, and also showing a group of detachable cable-connections similar to those in Figure 7.

Figure 9 is a plan view taken upon the line 9—9 of Figure 7.

Figure 10 is a similar plan view taken upon the line 10—10 of said Figure 7.

Figure 11 is a detail of a resiliently-mounted guiding roller taken from Figure 7.

Figure 12 is a skeleton view, showing more clearly the operation of the dials by the friction-rollers, and showing the "zero-setting" mechanism for the dials.

Figure 13 is similar to Figure 12, showing the "zero-setting" mechanism for the dials in operation.

Figure 14 is a wiring diagram showing the electrical arrangement.

Figure 15 is a perspective detail of special contact springs or relays serving to carry

the revolutions of one dial over to the dial of the next higher order.

Figures 16 and 17 show a longitudinal and a cross section, respectively, through a typical electromagnet as used for the operation of the escapement-rockers in the counter.

An Underwood typewriter, Figure 2, includes a machine-frame 20, a carriage 21 to support a platen 22 for lateral movement upon said machine-frame, said carriage having a rack 23 engaging with the well-known escapement-pinion 24, which, by means of a bracket 25, is mounted upon the machine-frame and connected with the well-known escapement-wheel 26 to be controlled for line-space movement of the carriage by the escapement-dogs 27 and 28 at every depression of a type-key 29 or of the letter-space bar 30.

The depression of a type-key will, through key-levers 31 and a bell-crank 32, cause a type-bar 33 to hit said platen for printing a letter and simultaneously to hit a universal bar 34. The universal bar will vibrate the escapement-dogs 27, 28 through arms 35 and a rocker-frame 36 alternately into engagement with said escapement-wheel 26 and allow the platen-carriage to proceed by letter-spaces, said carriage being urged by the pull from the usual spring-drum 37 and a draw-band 38. When using the letter-space bar 30, depression thereof will cause a space-bar lever 39 to hit a lower extension 40 upon said rocker-frame 36, and to vibrate the same for letter-spacing in the manner described. The escapement-dog 27, which is pivoted at 41 upon the associated escapement-dog 28, normally engages upon a tooth 42 of the escapement-wheel 26 to hold the carriage, see Figure 3. Upon depression of a type or space key the dog 28 is vibrated and thereby intercepts the tooth 42, see Figure 4, while the dog 27, now released, snaps past said tooth due to spring-tension 43, and into a position for engaging upon the next following tooth 44 when the key-pressure is released and the dogs swing back to normal position. In the Underwood machine the elements of the escapement-mechanism, from the pinion 24 down to the rocker-frame 36, happen to be mounted unitarily upon said bracket 25.

The vibration of the dog 27 about its pivot 41 is utilized to actuate a novel electrical contact-device 45 to be mounted upon said bracket 25 and designed to send a primary impulse to the word-counter at every type or space bar stroke.

The contact-device 45 constitutes a unit easily attachable to a standard Underwood machine at the rear thereof. This contact-device will not impair the touch of the machine while being vibrated by said carriage-escapement dogs 27 and 28, in other words, vibrated indirectly through the auxiliary power of the spring-drum 37 which ordi-

narily drives the carriage for letter spacing. The contact-device will respond indiscriminately at every type or space bar stroke whenever a type-bar 33 strikes the universal bar 34, 5 and vibrates the dogs alternately into engagement with the escapement-wheel 26, or whenever the space-bar lever 39 vibrates the rocker-frame to the same effect. The contact-device includes a bracket 46 having bent-down ears 47 to embrace said bracket 25 and having screws 48 thereon to secure the contact-device in place. The bracket 46 carries at the top a stub-shaft 49 secured in place by a round nut 50, the stub-shaft at its free end 10 terminating in a crank-arm 51 and a crank-pin 51^a, which latter extends into contact with the escapement-dog 27 and is held thereon by a tension-spring 52 fastened upon said nut 50 while flexed into a groove 53 thereon, and anchored at 54 upon said bracket 46. The rear end of said stub-shaft, which, in fact, is formed by said round nut, carries a finger 55 including a stem 56 terminating in a cap 56^a of non-conducting material, as hard rubber or the like.

The dog 27, vibrating in a well-known manner about its pivot 41 at every type and space bar stroke, will consequently cause the finger 55 to vibrate accordingly, and thus 15 actuate the electrical switch or contacts proper, which are located between two hard rubber blocks 57 and 58 mounted upon said bracket 46. This switch includes a fixed terminal 59 formed by a screw threaded into the one hard rubber block 57, and a spring terminal 60 in the form of a U-shaped flat spring of suitable material, a contact-point 61 of suitable material being indicated at the end of said spring. The spring is mounted by 20 means of a plate or clip 62 and screws 63 upon the movable wing 64 of a metal hinge, the other wing 65 of said hinge being fastened upon the other hard rubber block 58 by means of a screw-bolt 66, which incidently forms 25 part of this terminal, as can be seen from Figure 3, and which may have nuts 67 for the connection of a cable-conductor 68. Due to a light torsion spring 69 coiled around the hinge-bolt 70, said hinge has a tendency to 30 spread open, and thereby to close the switch. Normally it is held in open position by the actuating finger 55 engaging upon the upwardly-projecting end 71 of the movable hinge-wing and because the dog 27 is normally held engaged upon a tooth of the carriage-escapement wheel 26. As a type-key or the space-bar is depressed, the dogs 27 and 28 will vibrate. It is clear now that upon 35 depression of a key, the actuating finger is swung away from the switch and allows the same to make contact, see Figure 4. Upon releasing a key, the pull of the carriage will return the dog 27 to normal position, and thus also return the switch to normal open 40 position, see Figure 3. While not influenced

by the touch of the machine, the contact-device is designed for snappy and precise operation.

The word-counter is arranged to register two words at every tenth typewriter-stroke, 45 five strokes to a word being a well established average for ordinary typewriting and an accepted rule in typewriter-speed contests.

The counter may be compactly housed in a box the size of about 16×14×14 inches, 50 and which includes a baseboard 72, a cover 73, studs 74 upon said base-plate to position the cover thereon, and suitable means (not shown) to secure the cover upon the base. An opening or window 75 in the cover, see 55 Figure 1, is large enough to display a row of numerals 76 provided upon four dials 77, 78, 79, 80, which count the "units", "tens", "hundreds" and "thousands", respectively, i. e., to show up to the fourth decimal order 60 the number of words written at the time, said numerals with present dimensions of the counter showing up large enough to be read from a distance, while an upper and a lower row of Christmas-tree lamps 80^a within the 65 casing may lighten up the window from within for still better visibility of the numerals. Reflector plates 81 are provided to form a partition between the lamps and the adjacent dials. Along with the four dials there 70 is provided a plain wheel 81^a, i. e., a wheel without numerals, which takes the part of a fly-wheel to assist in rotating the relatively heavy dials in a manner to be described.

The boxed counter forms a self-contained unit including all the necessary mechanical and electrical equipment, as motors, magnets, resistances, as will hereinafter appear. The counter will be operative with merely an electrical connection indicated by the plug-connection 82 (see Figure 9) leading to the source of power preferably 110 volt D. C. current, and another connection leading to the typewriter which imparts the primary impulse to the counter at every type-bar or space-bar stroke, the latter connection being indicated by a plug-connection 84 (see Figure 9) as well as by said cable-conductor 68 (see Figure 2).

Every type or space bar stroke sends its impulse to a "strokes-device" 85 located within the counter and seen best in detail, Figure 5. The "strokes-device" is an escapement-device designed to properly respond to every one of a sequence of rapid typewriter-strokes, assuming, for instance, thirteen strokes per second to be a maximum obtainable, and so as to register by means of a main relay-switch 86 every tenth stroke in the units dial 77 as an equivalent of two words written. The fact that the units dial 77 responds at every tenth stroke only, will prevent fouling of the counting mechanism, as may occur when rapidly operating a typewriter, owing

to mechanical limitations, particularly the inertia of the dials. With the present arrangement, the counter has ample time to catch up with the typewriter while simply counting two words at a time. In other words, the units dial 77 counts in two's, and one revolution of the dial is equivalent to twenty words to be run into the register. Hence after ten words written, that is, after each half-revolution, this units-dial will run in a number on the adjacent dial 78, which is normally numbered from zero to nine. All the dials are electrically interconnected by suitable carry-over mechanism later on to be described.

The momentary closing of the typewriter-contacts upon a key-depression starts an impulse or current to said "strokes-device". From the source of power or main supply line 87 (see wiring diagram Figure 14), through a conductor 88 over said typewriter-contacts, through a connection 89 to a resistance lamp 90, and on through a conductor 91, the current energizes the solenoid of an electromagnet or "strokes-magnet" 92 which has a ground-connection 93. This "strokes-magnet" forms part of said "strokes-device" and has in parallel connection therewith a condenser 94 of a suitable capacity, which eliminates sparking at the contact points of the switch, sparks being liable to cause "sticking" of the contact point or destruction thereof at constant rapid operation. The condenser is shown to be mounted at the rear of the counter, see Figure 1. The electromagnet has a soft iron core or plunger 95 (Figure 9) which vibrates an escapement-rocker 96 built in the form of a light wire structure and co-operating with an escapement-wheel 97 which has a tendency to rotate in the direction of the arrow thereon, Figure 5, said rocker being pivoted upon a post formed by a screw-bolt 99 anchored upon a plate 100 which, in turn, is screwed at 101 upon a wooden supporting structure forming part of the framework of the counter, and including the beams 102 and 103. There is also provided a rigid wooden block 104 to support said electromagnet 92 by means of an angular mounting or clip 105 and screws 106. While the rocker thus is pivoted for horizontal movement, guided by a slotted plate 107, supported on posts 108 and 109, said rocker may be rocked by the underlying magnet 92, inasmuch as a portion 110 of the escapement-rocker reaches downwardly through an opening 111 in the magnet-core 95. A flexed coil-spring 112 forms a simple, flexible connection between said rocker-portion and said core, and will prevent undue play in the connection, such as may result in inaccurate operation of the escapement-rocker 96.

Through the electromagnet 92 each impulse from the typewriter vibrates the rocker 110 against spring-tension 112^a and thus advances

said escapement-wheel 97 by one tooth. Ten teeth 113 being provided upon the escapement-wheel, it takes consequently ten impulses from the typewriter, as required, or one full revolution of the escapement-wheel 97 to operate the above-mentioned main relay-switch 86, see detail Figure 9, in order to actuate the units-dial 77 to register two words written. A rod or switch-actuator 114 rotates with said escapement-wheel 97, the actuator camming over an arm 115 of a rock-shaft 116, thereby causing another arm 117 upon said rock-shaft to bridge over the ends of two contact-springs 118, 119.

The moment of tripping the main relay-switch is indicated in dot and dash, while it is understood that as the rod or actuator 114 travels past said arm 115, the other arm 117, by reason of its mere weight, will drop out of contact with the contact-springs 118, 119. The relay-switch 86 momentarily energizes the first one of a row of electromagnets 120, that is the one associated with the first or units-dial 77, to advance the same a step. A suitable condenser 121 is connected in parallel with said relay-switch 86 for purposes the same as mentioned above, that is to say, for eliminating electrical ill effects when operating the sensitive switch.

Auxiliary power for rotating said escapement-wheel 97 is furnished by a motor 122. The motor is constantly energized through a weak current coming from the supply line 87 over a suitable resistance 123 through a conductor 124 over said motor 122 to a ground connection 125 (see wiring diagram Figure 14).

Thus the motor represents a potential energy which constantly tends to rotate said escapement-wheel 97, which, by means of a sleeve 126 integral therewith, fits loosely over a motor-shaft 127 and which carries radiating therefrom said rod or switch-actuator 114. The sleeve is connected with the motor-shaft through a friction-clutch or friction-device 128, which allows for relative slippage between the sleeve 126 and the motor-shaft, in order to prevent shocks from the intermittent movement of the motor-shaft to be carried into the escapement proper, and to insure smooth operation of the "strokes-device". Two friction-blocks 129, 130 of the friction-device are tensioned upon said sleeve by a torsion spring 131 and have connection with a collar 132 fastened to the motor-shaft by a set-screw 133. The connection is shown as an angular piece of wire 134 with one end portion lodging within said torsion spring 131 and the other end portion engaging in a hole upon said collar 132.

The motor will exert its tension upon the escapement-wheel 97 each time the rocker 96 operates, and, since the motor-shaft is allowed to slip relatively to the escapement-wheel 97, the momentum of the armature will

be smoothly taken up in the friction device and not react on the escapement-mechanism proper. In practical operation the "strokes-device" will be operated in so rapid a succession that the motor-armature will not come to a dead stop but merely fluctuate while alternately slipping and feeding. Cable connections 136 and 137 for the motor 122 and for the magnet 92, respectively, are shown to 10 terminate in plugs 138 and 139 for ready disconnection and connection to and from the wiring system of the counter, including resistance lamps 139^a such as are arranged in rows at the rear of the counter upon the base-board 72 and upon a shelf 140 carried on standards 141.

The "strokes-device", as described, has merely electrical connection with the further working parts of the counter. It is, however, 20 suitably placed within the dials for compactness, together with driving mechanism for said dials.

Rigid framework of the counter rests upon a felt pad 142, placed upon the baseboard 72 25 in order to subdue vibrations caused by the actuating mechanism of the counter. The framework closely surrounds the cylindrical surface of the dials 77, 78, 79, 80 and the fly-wheel 81^a, and is built up of four corner 30 columns 143, 144, 145, 146, each pair of columns connected by beams 147, 148, and 149, 150, said columns furthermore interconnected by the beams 151, 152, 153, 154 completing the outline of an approximately cubic 35 structure. There is provided intermediate bracing in the form of additional columns 155, 156, 157, and additional beams 158, 159. A transverse frame 160 includes the elements 161, 162, 163, 164, forming further part of 40 the rigid structure of the framework, while a similar frame 165 includes the members 166, 167, 168, 169, and is arranged to float within said rigid framework. Movement of the floating frame is limited in one direction by 45 the stops 170, 171, and in another direction by the frame-elements 167 and 169 being confined between the rigid beams 150, 159 at the top and 158, 149 at the bottom of the general framework. The base plate carries studs 50 171^a by means of which to locate the cubic framework when placing the same upon the base plate.

Two pairs of roller-shafts 172, 173 and 55 174, 175 extend within the dials to support the same for their rotary movement. The one pair of roller-shafts is journaled in the rigid transverse frame 160, while the other pair is gathered in the floating frame 165. Through tension-springs 176, 177 the floating 60 frame is connected to the rigid framework at each side thereof, and constantly urged outwardly so as to hold all the rollers upon said roller-shafts in proper frictional contact with their dials 77, 78, 79, 80 and with 65 the fly-wheel 81^a, respectively. The two

upper shafts 172, 174 constitute a friction-drive for the dials, with a pair of friction-rollers 178, 179 to drive each dial, and a pair of similar friction-rollers 180, 181 to drive the fly-wheel 81^a. Endwise movement of the 70 shafts is limited by a sleeve 182 upon each shaft. The two lower shafts 173 and 175 are mounted correspondingly and fitted with rollers 183 spaced by sleeves 184, which rollers merely take the part of idlers. These shafts 75 are axially confined between end plates 185 screwed upon the supporting elements of the framework. The upper friction-rollers are spaced from each other upon their shafts by means of plates 187 screwed at 188 upon one side face of the rollers, and shaped so as to engage in grooves 189 upon said shafts. The other side face of each roller, shown clearly in Figure 12 and Figure 13, carries a friction-device 190 similar to the one employed in the above-described "strokes-device", and by means of which they are connected to their shafts. The device includes 80 blocks 191, a torsion-spring 193 by which the blocks are tensioned upon the shaft, and as an 85 additional element, an auxiliary spring 194 by means of which to adjust the tension, said spring coiled around a screw-bolt 195 and held compressed by nuts 196. Each driving friction-roller for the dials is furthermore 90 equipped with an arresting pin 197 slidable in bearings 198 mounted in the one side face of the roller. A compression-spring 199 coiled around said pin 197 normally urges the pin to protrude from the roller for the 95 purpose of retaining the roller in idle condition, as said pin rests against one of a row of escapement-studs 200, circumferentially provided in a groove 201 upon each dial. The 100 dials in turn are normally locked by electro-magnetically controlled escapement-rockers 202, while the roller-shafts 172 and 174 are constantly running against the tension of the 105 brake-device 190 and driven by a motor 203 through the twin-sprockets 204, 205 fixed 110 upon a motor-shaft 206, and further through driving chains 207, 208 and large sprocket-wheels 209, 210 fixed upon the floating ends of said shafts 172, 174. Chains are chosen 115 as a means of transmission in order to insure the positive rotation of the roller-shafts, particularly the shaft 174 which floats.

The motor 203 draws its power from the main supply line 87 (see wiring diagram Figure 14) over two resistance-lamps 213, 214, both lamps having parallel connections, whereby provision is made for cutting out one of the lamps by means of contact-springs 215, 216, in order to cut down motor-power for purposes to appear.

There is no escapement to hold the fly-wheel, and the latter therefore is constantly driven by its friction-rollers 180—181, and will tend to equalize fluctuations in the drive whenever the dials are actuated. Through 130

lateral contact with the adjacent dial and through it and successive dials it will tend to accelerate the rotation of the dials whenever the same are released to run in numbers.

5 A set of four guiding rollers 217, 218, 219, 220 is provided at either side of the counter. The rollers are pivoted on bearing blocks 221, 222, 223, 224 mounted upon the framework and are to insure the dials against 10 due lateral displacement within the framework, while excessive lateral friction between the dials is reduced by anti-friction rollers 225 as indicated in Figure 1 and Figure 9. Two of the guiding rollers, i. e., 218 and 220, see Figure 9 and detail Figure 11, may be resiliently mounted to insure contact with the adjacent faces of the outer dials. Detail Figure 11 shows the bearing block 222 pivoted at 226 and tensioned by a straight 15 wire spring 227 which is fastened to said block and extends downwardly along the respective column 155 to slidably engage upon a pin 228.

20 The driving motor 203, together with the above-mentioned "strokes-device", is supported upon said beams 102 and 103, which in turn rest on cross-pieces 229 at each end, mounted upon footings 229^a, said driving motor 203 having a cable-connection 230 terminating in a plug 231 for convenient hook-up to the wiring system of the counter.

25 The "strokes-device" 85 and the driving motor 203, while compactly housed within the dials, may be readily mounted or dismounted by removing the same together with the supporting beams 102, 103 and the cross-pieces 229, as may be seen from Figure 5 and Figure 6. There is furthermore provided a third beam 232 centrally arranged between said 30 beams 102, 103 and mounted by means of clips 233 and screws 234. This third beam carries upon its lower side additional relay-spring contacts. These contacts are closed, that is, bridged at due times by the dials to 35 function so as to carry a full revolution of a dial over to the dial of the next higher order, as will be presently explained.

40 Each of the four dials is controlled for stepwise movement by an electrically-operated escapement-rocker 202, such as mentioned above. The rocker is pivoted at 235 upon a bracket 236 which also carries fastened thereto by a screw 237 the associated electromagnet or solenoid 120. A loose core 239 of the electromagnet has a link-connection 240 with the lower portion of the rocker and vibrates the same whenever the magnet is energized (see dot-and-dash position, Figure 12). By means of said bracket, the electromagnets and their associated rockers are 45 mounted upon a supporting plate 241. At its upper end each rocker is held by a tension-spring 242 anchored upon said supporting plate at 243, said spring normally urging 50 the lower angular portion of the rocker 202

to intercept one of the escapement-studs 200 of the associated dial. Thus all the dials will be normally held in place against the tendency of the friction-rollers to rotate the same, until a period of ten key-strokes or impulses 70 of the typewriter is completed. Every tenth stroke will, over the "strokes-device" 85, operate the main relay-switch 86 and momentarily establish a current coming from the main supply line 87 over a resistance lamp 244, a conductor 245, said relay-switch 86, and a conductor 246 to the solenoid 120 of the first or units dial 77, to terminate in a ground connection 246^a.

75 The pulling stroke of the magnet-core is 80 rigidly limited by the rockers 202 abutting against a flat bar 247 rigidly suspended from the supporting plate 241, while normally the rockers rest against pads 247^a upon the supporting plate.

85 The rocker 202 in releasing an escapement-stud 200 will allow the first dial to be advanced by its friction-rollers, and will intercept the next following stud, said studs, ten 90 in number, being equally spaced over the circumference, so as to allow the dial to be advanced in steps, for instance, from four to six, see Figure 1, which means the registering of two words written.

95 The following will explain more clearly 95 the method of carrying over the revolutions of one dial to the dial of the next higher denomination.

100 When in the manner described, a period of ten words has been run into the first dial, i. e., a period equivalent to one-half revolution of said dial, a contact-member upon the dial formed by a wire 248, connecting two escapement-studs 249, 250 (see Figure 15 and wire diagram, Figure 14), will have come to 105 proximity with a pair of associated carry-over contact-springs 251, and as the dial enters its next period upon the second half of the dial, the contact-springs 251 will be momentarily bridged by contacting with said escapement-studs 249, 250 and establish a current from the main supply line 87, over a conductor 252, through said wire 248 and the contact-springs 251, and a conductor 260 over a lamp-resistance 254, to actuate the escape- 110 ment-magnet which serves the next following dial 78, which is the dial counting the "tens" and which is to be advanced a step so as to register the ten words written. It is understood that there are provided two 115 such wires 248 diametrically opposed upon the first or units dial, since one-half revolution of the dial forms a period of ten words, and the dial has a double array of numbers counting 0-2-4-6-8 only.

120 In the same manner, another pair of contact-springs 255 will be operated after the "tens" dial has completed one full revolution stepwise running in the numbers from "0" to 125 "9", and will send a current from the same 130

supply line 87 through a conductor 256, a resistance-lamp 257, and a conductor 258 to the following magnet 120 running in the "hundreds" on the dial 79. The last pair of contact-springs 251, controlled by said "hundreds" dial 79, will analogously run in the "thousands" on the last dial 80 by sending a current through conductor 253, a resistance-lamp 261 and a connection 262, to the last escapement-magnet, all the escapement-magnets having common the ground-connection 246.

The carry-over contact-springs, it is noted, are made up of loops of piano wire which prove to make satisfactory contact while only moderately tensioned so as not to unduly impair the advancement of the dials. It also proves to be superior to flat spring-contacts which are liable to become pitted at the contact points while the contact operates rather slowly. In the case of a flat contact-spring consequently the spring material may break at the contact points, and catching on the escapement-studs 200 may crumple up and foul the counting mechanism. All the cable-connections to the carry-over contact-springs are gathered in a plug or terminal 264 for convenient connection to the wiring system of the counter. In the same manner all the connections to the electromagnet 120 are joined in a plug 265, (see Figure 8).

It is required that all the dials be set to "zero" position at the beginning of each typewriter-speed-test. To this end, a push-rod 266, which may include a detachable upper portion, may be depressed to actuate "zero-setting" mechanism such as will be now described. (See Figures 1, 10, 12 and 13.)

Each dial has rigid therewith a zero pin 267 projecting inwardly from the interior surface of the dial. By means of these pins co-operating with a rear metal edge 268 of the above-mentioned supporting plate 241 the dials may be aligned for zero position. The plate 241 is the one which carries the electro-magnets 120 and rockers 202 controlling the dials, and is slidable back and forth between blocks 269 fastened upon the framework, that is upon the members 161, 166, 168, 163 of the framework, which also serve to limit the movement of said plate. The plate 241 is withdrawn from normal position, Figure 12, to the rear, see Figure 13, as the push-rod 266, having a knob 271 and guided in a bracket 272 upon the column 155, rocks an arm 273 fixed upon a rock-shaft 274 journaled in bearing members 275 outside upon the framework. Said rock-shaft terminates at each end in a crank-arm 276 which is connected through a link 277 to the slidable supporting plate 241, said link 277 formed by two members 278, 279 of flat material rigidly joined by slot-and-screw connections 280 such as will permit to vary the length of the link 65 for adjustment. The one end of said link is

pivoted at 281 within a slit of said crank-arm 276 while the other end swings about a shoulder-screw 282 threaded into a socket 283 which is mounted upon the side of said supporting plate 241.

When operating the "zero-setting" mechanism (see Figure 12 and Figure 13), manual pressure upon the push-rod 266 withdraws the sliding plate 241 to the rear and thereby disengages all the escapement-rockers 202 from their respective dials, thus setting the driving friction-rollers 178, 179 free to rotate all the dials until they are stopped by the "zero" pins abutting and lining up upon the rear metal edge 268 of said sliding plate, which now interposes in the path of said "zero" pins. The metal edge 268, it should be noted, is made of hardened steel in the form of a blade, and has sufficient resiliency to dampen shocks from the "zero" pins abutting thereon.

While the push-rod is held depressed against the tension of a spring 284, attached upon said pivot 281 of said crank-arm 276 and anchored upon a bracket 285 upon the framework, all the "zero" pins have a chance to properly line up upon said metal edge. Upon releasing said push-rod, the plate on its return to normal will free the "zero" pins and cause the rockers 202 to re-engage upon the proper escapement-studs 200, i. e., those which means "zero" position of the dials.

From the operating view, Figure 13, also appears best the purpose of a shield-plate 285^a fastened upon the members 161, 163 of the framework, see the side views Figure 7 and Figure 8, and also the purpose of thin metal strips 286 fastened on top of the sliding plate 241 by screws 287, each of these metal strips extending underneath the shield-plate 285^a and underneath a pair of associated friction-rollers 178, 179. The object is to thus ward off the arresting pins 197 of the friction-rollers and to prevent the pins from interfering with the rockers 202 or their springs 242 when the friction-rollers are actively rotating. For an arresting pin will be pushed in against the tension of the spring 199, as said pin cams over said shield-plate 285^a and the metal strips 286, respectively. Extending underneath the right-hand friction-roller, see Figure 13, the strip 286 is merely to protect the sliding plate against being scratched or worn by the impact of the tip of the arresting pin when the roller is rotating. The resiliency of the pin 197 is furthermore useful in that it prevents the pin from possibly getting jammed and stuck against an escapement-stud 200. Cut-outs 288 in the shield-plate 285^a provide clearances for the "zero" pins 267 when rotating (see dot-and-dash position of a "zero" pin in Figure 10).

The movement of the sliding plate 241 is also utilized to operate a switch including

the above-mentioned contact-springs 215, 216 fastened upon the frame-member 163 at the right-hand side of the counter, and a contact-plate 290 fastened correspondingly upon the right-hand side of said sliding plate 241. This contact is normally closed, see Figure 8 and Figure 12. However, while the "zero-setting" mechanism is operated, the contact-plate 290 will withdraw, together with the plate 241, and break the connection to the resistance-lamp 213 mentioned above, in order to temporarily cut out part of the power supply to the driving motor 203, and thus to dampen the shock resulting from the "zero" pins abutting against the metal edge 268. Releasing the push-rod will restore the contact and cause the motor to run again under normal power.

The various operating groups of the counter may be easily connected to the wiring system within the counter by flexible cable connections terminating in plugs, as has been described, and so as to facilitate assembling and disassembling thereof. A view upon the left-hand side of the counter, Figure 7, shows a 2 pole plug 291 for the Christmas tree lamps 80^a which are shown to be connected in series and to have positive and negative connections 292, 293, (see wiring diagram Figure 14), and furthermore, the 2 pole plug 231 for the driving motor 203 and the 2 pole plug 138 for the "strokes-motor" 122. These three plugs are combined in a common socket 294 secured upon the standard 141 of the lamp-shelf 140 at the rear of the counter. The right-hand side of the counter, Figure 8, shows in a similar way a common socket 295 for a 2 pole plug 296 for the contact-springs 215, 216, the 5 pole plug 265 for the escapement-magnets, a 2 pole plug 297 for contacts 118, 119 of the main relay-switch 86, another 4 pole plug 264 for the carry-over contact-springs 251, 255, 259, and the 2 pole plug 139 for the strokes-magnet 92. The correct connection between all of these plugs and their respective sockets may be insured by means of markings upon the plugs which are to be brought to match with corresponding markings on the sockets and shown as arrows 298 pointing under different angles. All of these plugs are furthermore indicated in the wiring diagram, Figure 14, in dot and dash, and so as to show clearly the detachability of the various operating groups from the wiring system.

To give visible indication that every stroke upon the typewriter properly reflects in the counter, there may be provided a "strokes-lamp" 299 flashing up at every type-stroke and mounted in a socket 300 visible on top of the counter-box, see Figure 7. The "strokes-lamp" is indicated in the wiring diagram as having a positive and a negative connection 301 and 302, respectively. Since the cover of the counter-box is detachable,

provision is made for a cable 302^a leading within the cover from the "strokes-light" through a hole 303 in the rear wall and down to terminate in a plug 304 which may be connected to a socket 305 fastened upon the base-board 72, as seen in plan view, Figure 9. Upon said base board there is also shown a socket 306 for connecting the counter with the typewriter, and another socket 307 for connection to the power supply line.

In the diagram, Figure 14, there is also indicated an auxiliary switch or push-button 308 connected to the counter in parallel with the typewriting machine by conductors 309, 310. By means of the push-button one may operate the counter without handling the typewriter. Every touch upon the button imparts an impulse to the counter analogously to a key-depression upon the typewriter. This arrangement may be useful for trying out the counter or when clearing the same whenever a speed-contest is started. It may occur that although the dials are returned to "zero" position the "strokes-device" has not finished a period of ten strokes, in other words, the rod 114 in the "strokes-device", which actuates the main relay-switch 86, just happens to be in an intermediate position. A few depressions upon the push-button therefore will clear the "strokes-device", that is, position the same for beginning a period of ten words in accordance with the "zero" position of the units dial. Hence an operator will first clear the "strokes-device" by operating the push-button until the end of a "strokes-period" is reached, and then clear the whole counter by reducing the dials to "zero" position through a depression of the push-rod 266. A plain switch 311 allows the typewriter to be disconnected from the counter when preliminary writing is to be done before starting a contest on the counter.

With the proper selection of motors, resistances and magnets, the word-counter may be operated on D. C. as well as A. C. current. In Figure 16 are shown the details of an escapement-magnet which is adapted for the use of both kinds of currents. The coils 312 of the solenoid are entirely encased in a metal casing which it is a general practice to use for intensifying the magnetic flux and which makes for an efficient magnet, said casing including an interior brass tube 313, disk-like end plates 314 and 315, and an exterior shell 316. A stub 317 is fastened upon the bracket 236 and fits tightly into said brass tube so as to support the solenoid. All the metal parts which are being permeated by the magnetic flux are slotted for the well-known reason of avoiding losses through turbulent or irregular currents, which are set up in the surface of these metal parts through the frequency of alternating current, and which are liable to impair the efficiency of the magnet. The rigid stop will prevent the

5 magnet-plunger from touching the bottom of the solenoid, that is, the stub 317, when energized, and will preclude the possibility of the magnet-plunger being pulled with too great a force, and also preclude the danger 10 of the plunger getting stuck through residual magnetism when touching bottom. With said brass tube not being susceptible to the magnet energy, the sliding movement of said plunger will not be hindered by magnetic friction.

15 In assembling the elements of the magnet the slotted disk 314 is sprung over the also slotted stub 317, and sprung over said stub is also the slotted brass tube 313, so as to abut against said disk. After the solenoid is applied, that is, slipped over the brass tube, the other disk 315 may be sprung over said brass tube as a front closure-piece, and hereafter 20 the exterior shell 316 sprung over the end plates 314, 315, as shown in the drawings.

25 The novel contact-device herein described takes into account certain conditions prevailing in typewriter-speed contests, as will be shown: work-sheets, as officially used in such contests, have marked thereon a standard number of letter spaces for each line, which aid in quickly summing up the number of letter-spaces or words written by the operator 30 and whereby credit is given to the operator for one letter-space at the end of the line, no matter whether or not she hits the space-bar at the end of the line. If therefore the operator has trained herself so as not to hit 35 the space-bar in order to save time, but to return the carriage right after the last letter has been written, she may have an advantage of one word, that is five letters at every fifth line over the contestant who is used to hitting 40 the space-bar at the end of a line. It will now be noted that with the novel contact-device the very return of the carriage will count for a stroke, since it allows one vibration of the dog 27, and thus will count for the last letter-space in accordance with the official work-sheets. While the second contestant, if she 45 really hits the space-bar, will get the deserved credit through an additional count in the word-counter.

50 Variations may be resorted to within the scope of the invention, and portions of the improvements may be used without others.

Having thus described my invention, I claim:

55 1. In a counter for adding the number of key-strokes of an alphabetical keyboard machine, the combination of a series of indicating dials arranged in a decimal series including a units-dial, all rotatably mounted in denominational order, a series of driving devices to rotate said dials, means including electromagnets, one for each dial to control said devices to rotate the dials to indicate the 60 number of key-strokes, circuits for the electromagnets, and a device, interpolated in the 65

circuit of the electromagnet for the units-dial including means to delay the operation of said units electromagnet until after a predetermined number of key-strokes of the keyboard.

70

2. In a counter for adding the number of key-strokes of an alphabetical keyboard machine, the combination of a series of indicating dials rotatably mounted in denominational order, a series of power-controlled friction wheels permanently bearing against said dials and tending to rotate the same, means to hold said wheels immovable when the dials are not rotating, and means responsive to the keys of said keyboard to control said wheels to rotate the dials for indicating the number of key-strokes.

75

3. In a counter for adding the number of key-strokes of an alphabetical keyboard machine, the combination of a series of indicating annular dials rotatably mounted in denominational order, dial-driving means including a series of friction rollers to bear against the inside of the annular dials to rotate the same, and means responsive to the keys of said keyboard to control said rollers for rotating the dials to indicate the number of key-strokes.

80

4. In a counter for adding the number of key-strokes of an alphabetical keyboard machine, the combination of a series of indicating annular dials rotatably mounted in denominational order, a series of friction rollers to bear against the inside of the annular dials, a plurality of driven shafts, to support 85 said rollers, journaled in said framework to rotate the rollers, and means responsive to movement of the keys of said keyboard to control said rollers to rotate the dials for indicating the number of key-strokes.

90

5. In a counter for adding the number of key-strokes of an alphabetical keyboard machine, the combination of a series of indicating annular dials rotatably mounted in denominational order, a series of friction rollers to bear against the inside of the annular dials to rotate the same, an electric motor also mounted within said annular dials, a series of means to rotatably engage the motion with said friction rollers, effective 10 to actuate each of said rollers, and means, responsive to the keys of said keyboard, to control said rollers to rotate the dials for indicating the number of key-strokes.

11

6. In a counter for adding the number of key-strokes of an alphabetical keyboard machine, the combination of a series of rotatable indicating dials, a plurality of series of friction wheels, one series for each dial, a plurality of rotating supporting shafts upon 12 which said friction wheels are rotatably mounted, friction devices between the shafts and the wheels to transmit motion to the wheels from the shafts and to permit the wheels to slip on said shafts when the dials 13

- are stationary, resilient means to press the wheels permanently in driving engagement with the dials, means to hold the dials immovable, and means responsive to the key-strokes of said keyboard, effective to release the holding means to allow the dials to rotate and indicate the total number of key-strokes.
7. In a counter for adding the number of key-strokes of an alphabetical keyboard machine, the combination of a series of indicating annular dials, driving rollers and idler rollers for each dial mounted within and bearing against the same to hold the dials in position, resilient means to spread the rollers apart to force them against the inside of the dials, said dials and rollers being normally inactive, a power drive to rotate the dials to indicate the total number of key-strokes, and means controlled by the key-strokes of said keyboard to initiate the movement of said dials.
8. In a counter for adding the number of key-strokes of an alphabetical keyboard machine, the combination of a plurality of indicating dials arranged in a decimal series, a series of rotating means, one for each dial, including an electric circuit responsive to key-strokes to control the rotation of one of the dials, electric contacts, and electrically-actuated rotation-controlling devices associated with the dials to control said rotating means, operation of each of said rotation-controlling devices being initiated by the contacts of the next lower dial in the series, and a stroke-grouping device interpolated in said circuit to control the rotation-controlling means of the first dial in the series, to index that dial after each group of a predetermined number of key-strokes.
- 40 9. In a counter for adding the number of key-strokes of an alphabetical keyboard machine, the combination of a plurality of indicating dials arranged in a decimal series, a series of driving means to rotate the dials, a series of electric controls therefor, one for each dial, a contact-maker actuated by each dial, effective to initiate the operation of the control of the dial next higher in the series, and a stroke-grouping device responsive to key-strokes of said keyboard, including an electric circuit connected to the electric control of the first dial in the series, to control the latter to index after each group of a predetermined number of key-strokes.
- 45 50 55 60 65 10. In a counter for adding the number of groups of key-strokes of an alphabetical keyboard machine, the combination of a series of indicating dials rotatably mounted in a decimal series, a series of driving devices to rotate said dials, and a mechanism for grouping the key-strokes responsive to the keyboard, to control said devices, including means responsive to a predetermined number of key-strokes and means actuated thereby after said strokes to initiate an indexing operation of said devices.
11. In a counter for adding the number of key-strokes of an alphabetical keyboard machine, the combination of a series of intermittently rotatable members having numerical indications thereon, an additional similar member having no indications and effective for continuous rotation, to act as a fly-wheel, means tending to rotate all of the members concomitantly, means releasably detenting the intermittently rotatable members from rotating, and means controlled by the keyboard for releasing the members and permitting them to rotate and index the total number of key-strokes.
12. In a counter for adding the number of key-strokes of an alphabetical keyboard machine, the combination of a plurality of indicating annuli arranged in a decimal series, a power drive including a shaft extending through said annuli, said shaft carrying friction rollers each bearing against the inner surface of an annulus and tending to rotate the annuli, permanently engaged by said power drive, into each of a plurality of numerical positions including zero-position to indicate the number of key-strokes, a detent for each annulus to retain it in indexed position, and means effective to release all of said detents simultaneously, to initiate a return movement of all of said annuli at will to the zero-position.
13. A counter comprising a series of denominational annuli each annulus being supported solely on its inner annular surface, and annuli operating means one for each annulus within the inner periphery of the annuli having friction surfaces contacting with the interior of the annuli, a motor for operating said means and denominational carrying means between successive denominational annuli for transferring from a lower to the next higher denomination.
14. A counter comprising a series of denominational annuli, and continuously revolvable friction means on the interior peripheries of the annuli for operating the annuli a motor for operating said means and denominational carrying means between successive denominational annuli for transferring from a lower to the next higher denomination.
15. A counter comprising denominational annuli and a flywheel annulus, means for continuously operating the flywheel annulus, said flywheel annulus being in frictional relation with the units annulus of the counter to constantly urge the rotation of the same and means to periodically release and then arrest the units annulus.
16. A counter comprising denominational annuli each annulus being supported solely on its inner annular surface and constantly rotating means in the open portions of the annuli to continuously urge rotation of the

annuli and denominational carrying means actuatable to periodically release and then arrest the annuli to transfer from a lower to the next higher annulus.

- 5 17. A counter comprising a series of denominational annuli, revolving means on the interior of each annulus in frictional relation therewith to constantly urge its rotation and denominational carrying means actuatable to periodically release and then stop the rotation of each annulus independently of the operation of the other annuli to transfer from a lower to the next higher annulus.
- 10 18. A counter comprising annular rings with open central portions and operating friction rollers in the open portions for engaging the interior peripheries of said rings, means to continuously urge the rotation of the rollers and denominational carrying means actuatable for releasing and then arresting the rotation of the rings to transfer from a lower to the next higher annulus.
